UNITED STATES PATENT OFFICE.

GUY H. PRESTON, OF THE UNITED STATES ARMY.

FIELD-RATION MESS-KIT.

No. 911,442.

Specification of Letters Patent.

Patented Feb. 2, 1909.

Application filed February 3, 1908. Serial No. 414,149.

To all whom it may concern:

Be it known that I, GUY H. PRESTON, captain United States Army, a citizen of the United States, residing at Fort Myer, in the 5 county of Alexandria and State of Virginia, have invented certain new and useful Improvements in Field-Ration Mess-Kits; and I do hereby declare the following to be a full, clear, and exact description of the invention, 10 such as will enable others skilled in the art to which it appertains to make and use the same.

My invention relates to field ration mess kits, and the object of my invention is to 15 make a field-ration mess-kit of such form and relative dimensions that the individual receptacles shall have the greatest possible utility, strength, and simplicity when used separately, and at the same time occupy the 20 smallest possible space when stowed for carriage. This object I attain, in part, by extending the mouth of the canteen in the form of the neck of a bottle of length sufficient to afford a grasp or handle for the 25 hand. To the shape of this neck, the handles of the various nested receptacles are made to conform so that they neatly fit about it when packed. The said handles being curved, or hollow, and made integral 30 with, or permanently affixed to, their respective receptacles enable me to do away with the necessity for complicated folding devices heretofore used while at the same time making them stronger, more durable, 35 and cheaper of fabrication. This I regard as a most distinctive and novel feature of this invention. The canteen proper is not covered, as is usual in military services, with felt or canvas, experience having proven that in 40 the small air spaces between it and the articles nested upon it there is provided an efficient non-conductor of heat to insure the retention of the liquid contents in a cool condition; and to accomplish this end, the 45 pans and cups are made to embrace the entire surface of the canteen, while breaking joints, so as to effect a complete inclosure, and at the same time shut out warm air.

The assembled kit is carried in a case of 50 canvas or other material, adapted to be wetted for the evaporative cooling of the contents of the canteen, all as will more fully appear hereinafter.

Referring to the accompanying drawings 55 forming a part of this specification and in

which like numerals designate like parts in all the views:—Figure 1, is a perspective view of my field ration mess-kit when taken from its case, showing the parts in their nested condition. Fig. 2, a perspective 60 view of the parts ready to be nested. Fig. 3, a view of the case adapted to receive the parts as shown in Fig. 1, and showing the disposition of the knife, fork and spoon. Fig. 4, a detail showing how the knife, fork, 65 or spoon may be used as a lifter to hold the hot cooking utensils, and Fig. 5, a detail of the neck of the canteen, showing how the neck of the case and the handles of the utensils nest there around. 70

The individual parts may be made of any suitable shape and of any suitable material, but I prefer to make the canteen 1, of metal for soldiers' use, and of glass for campers or sportsmen's use, and to round all corners to 75 such an extent as will facilitate the manufacture and nesting of the said parts.

2, represents the neck of the canteen, which is preferably made sufficiently long to afford an easy grasp by the palm of the hand. 80

3, indicates a pan provided with a handle 4, and 5, another similar pan provided with a handle 6. These pans are each preferably made on their interior of dimensions one half 85 the outside dimensions of the canteen, so that they snugly fit and cover the outside of body portion 1, and the handles 5 and 6, are each likewise made of one half the outside dimensions of the neck 2, so that they snugly fit and cover said neck. 90

7, designates a cup, and 8, its handle. The body portion of the cup 7, is made of such a shape and dimensions that it will snugly fit over the ends of and cover one half of each of the bodies of the pans 3 and 5, after they are 95 nested on the canteen; and the handle 8, will likewise fit over and snugly cover one half of each of the handles 4 and 6, in their nested positions; thus covering the joints made by said pans and handles on one half of the canteen. 100

9, represents a receptacle adapted to fit over the other ends and to cover the other half of the pans 3 and 5, as well as the joint made by such pans on the other half of the 105 canteen. This receptacle 9, is provided with a half round notch 10, into which one of the handles 4 or 6, fits when in its nested position. Over the receptacle 9, the receptacle 11, is adapted to fit, and I may provide as 110

many receptacles 9 and 11, as is found desirable. These receptacles when taken in pairs make a good lunch box for greasy food, since they can be telescoped the one into the other 5 and carried in the saddle bag, haversack, pocket or other place if desired. These receptacles serve as extra receptacles at mess, and also to cool hot liquids.

When the parts are assembled as shown in 10 Fig. 1, the whole is slipped into the case 12, the neck 13, of which fits over the neck 2, and handles 6 and 8, in their nested position, and the hinged bottom 14, of which closes around the bottom portions of the nested kit, to be 15 fastened by the buckle or other fastening means 15.

In the bottom 14, are accommodated a 20 knife, a fork and a spoon 16, as shown, each of which is provided with a handle having a bent projection, or lug 17, adapted to fit into the holes 18, made in each of the handles 4, 6 and 8, as shown, very much like a stove lifter fits into the lid of a stove; and they thereby afford a means of readily handling 25 each of the cooking utensils 3, 5 and 7, while hot.

The neck 2, of the canteen is preferably provided with a bead 19, having a flat under-surface, against which the top edges 20, of 30 the handles 4, 6 and 8 fit, and thereby prevents liquid from running down between the cooking utensils and the canteen when dripping from the mouth of the said neck 2.

The neck 13, of the cover is provided with 35 a ring 21, to afford a stiffening means to aid in pulling the cover off and on the kit proper. 22, is one of two rings to afford means for suspending the kit, from the person or from the saddle as desired.

40 It will thus be observed that I have produced a mess-kit having handled cooking utensils, as in my former patent No. 555,882, March 3, 1896, but that I do not have to employ the hinges that have been found to be so 45 objectionable in that patent. Furthermore, I provide a suitable handle by which both the canteen and the nested utensils may be readily grasped at all times, which desirable feature is not present in my former patent.

50 The peculiar tapered shape of the handles 4, 6 and 8, serves to greatly strengthen the same, and when the parts are pressed out of sheet steel the utensil and handle make an exceedingly rigid and stiff structure capable 55 of standing any amount of rough usage.

It is quite easy for the soldier to overlap two handles 4 and 6, or 4 and 8, hold them in one hand, and thereby present two receptacles at the serving out place, instead of one.

60 I may employ any suitable stoppering means for my canteen, the cork 12, being merely shown as a conventional means.

I do not wish to be understood as limiting 65 my invention to the exact details of construction and arrangement of parts above set

forth, since it is evident that both may be widely varied without departing from the spirit of my invention.

What I claim is:—

1. In a field ration mess-kit, the combination of a receptacle having a neck, and a second receptacle suitable for cooking food adapted to closely fit the outside of said first receptacle and having a handle adapted to closely fit said neck, substantially as described. 76

2. In a field ration mess-kit, the combination of a receptacle, having a neck, and a plurality of other receptacles suitable for cooking purposes adapted to closely fit and completely cover the outside of said first mentioned receptacle and each of said other receptacles provided with a handle adapted to snugly fit and cover said neck, substantially as described. 80

3. In a field ration mess-kit, the combination of a canteen having a neck adapted to be used as a handle; a plurality of cooking receptacles provided with handles adapted to snugly fit and cover the outside of said canteen and neck; and a third receptacle adapted to slip over a portion of said other receptacles when in their nested position, substantially as described. 85

4. In a field ration mess-kit, the combination of a canteen having a neck adapted to be used as a handle; a plurality of receptacles provided with handles adapted to snugly fit and cover the outside of said canteen and neck, and a third receptacle provided with a handle adapted to slip over a portion of said other receptacles when in their nested position, and the handle of said third receptacle also adapted to fit over a portion of the handles of each of said other receptacles, substantially as described. 95

5. In a field ration mess-kit, the combination of a canteen having a neck adapted to be used as a handle; a plurality of receptacles provided with handles adapted to snugly fit and cover the outside of said canteen and neck; a third receptacle adapted to slip over a portion of said other receptacles when in their nested position, and a fourth receptacle adapted to fit over said third receptacle, said third and fourth receptacles adapted to telescope into each other to form a lunch box, substantially as described. 100

6. In a field ration mess-kit, the combination of a receptacle having a neck and a second cooking receptacle adapted to closely fit the outside of said first receptacle, and having a handle adapted to closely fit the outside of said neck, and said handle having a hole adapted to receive a suitable lifting instrument, substantially as described. 115

7. In a field ration mess-kit, the combination of a canteen having a neck; a plurality of cooking receptacles provided with handles rigid therewith adapted to nest about the 120

130

outside of said canteen and its neck; said handles provided with holes, and a casing adapted to inclose and suspend said canteen and nested receptacles, and to accommodate 5 a spoon provided with a handle having a lug adapted to enter each of said holes, substantially as described.

8. In a field ration mess-kit, the combination of a canteen having a neck provided 10 with a lip; a plurality of cooking receptacles provided with handles rigid therewith adapted to nest about the outside of said canteen and neck and under said lip, and a casing adapted to absorb water when wetted, having 15 means to suspend said canteen and receptacles, and also adapted to store a fork, a spoon and a knife, substantially as described.

9. In a field ration mess-kit, the combination of a canteen having a neck provided with a lip; a plurality of receptacles provided 20 with handles rigid therewith adapted to nest about the outside of said canteen and neck and under said lip, and a casing adapted to absorb water when wetted, having a neck provided with a stiffening ring, and means to 25 suspend said canteen and receptacles, and also adapted to store a fork, a spoon and a knife, substantially as described.

In testimony whereof, I affix my signature in presence of two witnesses.
